[**] Term: 14 Years

[57] CLAIM

[21] Appl. No.: 845,356

The ornamental design for a base for a telephone subscriber set, as shown and described.

[22] Filed: Mar. 19, 1986

DESCRIPTION

[52] U.S. Cl. D14/62; D14/58;
D14/60; D14/57
[58] Field of Search D14/52, 53, 57, 58,
D14/60, 62; 379/419, 420, 428, 432, 434, 436,
440, 435

FIG. 1 is a right side perspective view of a base for a telephone subscriber set showing our new design with the flap open;

FIG. 2 is a right side perspective view thereof with the flap closed;

FIG. 3 is a top view thereof;

FIG. 4 is a bottom view thereof;

FIG. 5 is a front elevational view thereof;

FIG. 6 is a rear elevational view thereof;

FIG. 7 is a left side elevational view thereof; and

FIG. 8 is a right side elevational view thereof.

The handset, shown in broken lines in FIGS. 1, 2, and 6-8, forms no part of the present design.
